UNITED STATES PATENT OFFICE

WALTER GEHRIG, OF HIGHLAND PARK, MICHIGAN

SPOTLIGHT

Application filed July 28, 1930. Serial No. 471,237.

This invention relates to spotlights, and the object of the invention is to provide a spotlight adapted to be mounted on the cowl of an automobile and adapted for manual operation to turn the reflector of the spotlight in any desired direction.

Another object of the invention is to provide a support for the spotlight so arranged as to take the weight of the spotlight off from the cowl of the automobile.

A further object of the invention is to provide a spotlight of the character described which may be locked in any position to which it is turned.

15 A further object of the invention is to provide an arrangement whereby the spotlight may be turned completely around its vertical axis.

A further object of the invention is to provide a spotlight including a casing turnable about a vertical axis and a reflector mounted in the casing and pivoted on a horizontal axis, the said reflector being normally set at a slight angle in the frame.

25 A further object of the invention is to provide a spotlight having a control handle normally extending adjacent the instrument board of the automobile and adapted by movement to produce a corresponding movement of the spotlight.

These objects and the several novel features of the invention are hereinafter more fully described and claimed, and the preferred form of construction by which these 35 objects are attained is shown in the accompanying drawing in which—

Fig. 1 is an elevation partly in section showing the device as mounted on the cowl of an automobile.

40 Fig. 2 is an enlarged section through the spotlight and control mechanism.

Fig. 3 is a section taken on line 3—3 of Fig. 2.

45 Fig. 4 is a section taken on line 4—4 of Fig. 2.

Fig. 5 is a detail showing the locking device for the spotlight in the locked position.

Fig. 6 is a detail of the connection between the locking wire and the locking ring.

Fig. 7 is an elevation of the slotted clutch 5 member.

The device comprises a casing 1 formed of two halves as shown in Figs. 2 and 4 adapted to be secured together by means of the screws or bolts. One half is provided with an extension 2 having a central aperture for the tubular shaft 3 and provided with a flange at the bottom resting on the base plate 4. A reflector 5 is provided as shown in Fig. 2 having recesses 6 in opposite sides thereof adapted to receive trunnions 7 which extend inwardly from the casing 1. The axis of the recesses 6 extend at a right angle to the longitudinal axis of the casing 1 but the reflector is so positioned in relation to the recesses 6 that the axis thereof extends at a slight angle to the longitudinal axis of the casing 1 and tends to throw the light to the right curb when the casing 1 is pointed straight ahead as indicated by the dotted lines shown in Fig. 4.

The reflector 5 at the rear is provided with a pair of lugs 8 in which a pin 9 is secured and this pin extends through a slot 10 in the upper end of the shaft 3. The casing 1 is provided with a partition 11 having a slot 12 therein and the upper end of the tubular shaft 3 is provided with a flattened angularly extending end 13 which extends into and rides in the slot 12. By this arrangement upward or downward movement of the tubular shaft 3 will turn the reflector 5 on the trunnions 7 and the slot 10 is provided in the end 13 of the shaft 3 to allow the pin 9 to move in the slot during turning movement of the reflector. The portion 2 of the casing 1 is provided with a tubular sleeve 14 extending downwardly therefrom and the base plate 5 is provided with an annular rib 15 which extends up into the portion 2 and prevents

water from passing into the interior of the base plate 4 and sleeve formed integrally therewith. The sleeve 16 is stationary and is secured in position by means of the bolts 17 which pass through the base plate 4, cowl 18 and through the washer 19. The sleeve 14 fits within the sleeve 16 and the tubular shaft 3 extends upwardly through the sleeve 14 and member 2. The sleeve 16 at the bottom is provided with a groove 20, while the sleeve 14 at the bottom is provided with a groove 21. In order to hold these sleeves in proper relation, a bracket is provided comprising two halves 22 adapted to be secured together 15 and having portions engaging in the grooves 20 and 21 as shown in Fig. 2.

An arm 23 is attached to the bracket 22 and a bracket 24 is attached to the dash 25 of the automobile. The arm 23 is provided 20 with bolt slots 26 adapted to receive the bolts 27 and 28 and the bracket 24 is provided with an aperture for the bolt 27 and with an arcuate slot 29 for the bolt 28. By this arrangement the arm 23 may be firmly secured 25 in position to support the bracket 22 and take the weight off from the cowl 18 of the automobile.

A curved arm 30 is provided having an end 31 rotatable in the bracket 22 about the tubular shaft 3. The lower end of this arm 30 is pivotally connected to a bushing 32 in which a shaft 33 is slidable longitudinally. The shaft 33 is hollow as shown in Figs. 2 and 3 and is provided with a yoke 34 secured to 35 the end thereof. A U-shaped shoe 35 is supported between the ends of the yoke 34 and rides in the bottom of the groove 36 provided in the wheel 37. The groove 36 opens out into an angular faced groove 38 and the shoe 35 is provided with sloping friction faces 39 adapted to engage against the angular faces 38 of the wheel 37. By this arrangement the handle 41 and shaft 33 may be swung through a horizontal arc and will turn the tubular shaft 3 on its axis thus turning the casing 1 about the axis of the said shaft.

In order to lock the spotlight in any position, a conical slotted clutch member 42 is formed integrally with the bracket 22 and the shaft 3 extends therethrough. A clutch collar 43 is provided adapted to engage the clutch member 42 and an arm 44 is pivotally connected to the clutch collar 43 and to the arm 30. A rod 45 is pivotally connected to 58 the arm 44 and extends upwardly through the arm 30 and through a coil spring 46, and is provided with a washer and nut on the upper end thereof for adjusting the tension of the spring 46.

60 The spring 46 tends to draw the arm 44 upwardly and move the clutch collar 43 into engagement with the clutch member 42 as shown in Fig. 5. A toggle joint 47 is provided between the arm 44 and the arm 30 and this toggle joint is controlled by means

of a Bowden wire 48 which may be moved from the position shown in Fig. 5 to that shown in Fig. 2 to move the toggle joint as shown. When the toggle joint is in the position shown in Fig. 2, the lug 49 on the toggle joint limits movement of the said joint and when in this position the arm 44 is moved downwardly to disengage the clutch collar 43 from the clutch member 42. The Bowden wire is connected to a collar 50 which is slidable on the shaft 33 as shown in Figs. 2 and 6 and, by drawing this collar 50 to the left of Fig. 2 the toggle joint is drawn to the expanded position, while by moving this collar 50 to the right of Fig. 2 the toggle joint is moved to the collapsed position shown in Fig. 5.

When in this collapsed position, the spring 46 draws the arm 44 and clutch collar 43 upwardly to engage the conical slotted clutch member 42 which compresses the ends of the slotted conical clutch member 42 on the shaft 3 and causes this clutch member 42 to grip the shaft 3 and prevents movement thereof in any direction. By subsequently moving the sleeve 50 to the left of Fig. 2 the toggle joint 47 is expanded to disengage the clutch collar 43 from the clutch member 42, at which time the shaft 3 is freed and the handle 41 may be turned in a horizontal plane to turn the shaft 3 and casing 1 or may be moved up or down in a vertical plane to produce corresponding vertical movement of the shaft 3. As the coil spring 40 holds the clutch facing 39 in engagement with the wheel 37 the shaft 3 will turn with the handle 41 and arm 30 and slide up or down according to the vertical motion of the yoke 34.

If the operator wishes to turn the spotlight through a complete revolution on its axis, the ball 41 and shaft 33 may be drawn longitudinally to the left of Fig. 2 against the tension of the spring 40 to disengage the clutch faces 39 from the companion faces in the wheel 37 and while held in this position, the handle and shaft may be swung to move the clutch faces about the periphery of the wheel 37 and upon release of the handle the spring 40 will again move the clutch faces 39 into engagement in the groove of the wheel.

By this arrangement the spotlight may be turned through a segment of a circle and the clutch 39 may be then reengaged in the wheel 37 to move the spotlight through further segments of the circle. By pushing the handle 41 downwardly on its axis 51, the shaft 3 is moved upwardly thus turning the reflector 5 on the trunnions 7 to focus the light downwardly, while by upward movement of the handle 41 the shaft 3 is moved downwardly to turn the reflector to focus the light upwardly. By this arrangement the casing carrying the reflector may be turned about a vertical axis, while the reflector itself may be turned on its horizontal axis to direct the

rays of the light to any desired position. The wiring 52 is carried from a suitable source of current supply and through the hollow shaft 33 to the switch 53 as shown and the wire 52 is carried from the switch 53 through the shaft 33 thence upwardly through the tubular shaft 3 and into the interior of the reflector as shown at the upper end of Fig. 2.

10 Normally the casing 1 is locked in a "straight-ahead" position on the car and in this position the spotlight presents the best appearance for daylight driving and is, at the same time, in the position most used for 15 night driving, as in this position the light beam will be thrown to the right curb on account of the described angular mounting of the reflector. When the spotlight is adjusted and locked in this or any other position, the handle 41 and shaft 33 can be swung out of 20 way and out of view by disengaging the clutch faces 39 in the manner heretofore described and then swinging said handle and shaft through a horizontal arc to any suitable 25 position, such as, for example, below the dash board or underneath the cowl.

From the foregoing description it becomes evident that the device is very simple and efficient in operation, may be readily installed, provides a complete control of the spotlight from the interior of the automobile and provides a device which accomplishes the objects described.

Having thus fully described my invention, 35 its utility and mode of operation, what I claim and desire to secure by Letters Patent of the United States is—

1. In a spotlight, a stationary bracket, a vertical shaft rotatably mounted in the said bracket and movable vertically therein, a casing rotatable with the said shaft, a reflector mounted in the casing to turn on a horizontal axis, means connecting the shaft with the reflector and with the casing whereby 40 vertical movement of the shaft turns the reflector on its axis and rotation of the shaft turns the casing therewith, a portion of said bracket being shaped to provide a stationary clutch member, a movable clutch member, 45 yieldable means normally urging the movable clutch member into engagement with the stationary clutch member, the clutch members when engaging locking the vertical shaft from movement, manually operable means 50 for releasing the clutch members to allow movement of the vertical shaft, an arm rotatable about the vertical shaft, a lever pivotally and slidably mounted in the outer end thereof, a handle at one end of the lever, 55 a clutch member at the other end of the lever, a companion clutch member secured to the lower end of the vertical shaft, yieldable means urging said clutch members into engagement and manually operable means for 60 disengaging said clutch members.

2. In a spotlight, a stationary bracket, a vertical shaft rotatably mounted in the bracket, a casing rotatable with said shaft, a reflector mounted in the casing to turn on a horizontal axis, means connecting the shaft with the reflector and with the casing whereby vertical movement of the shaft turns the reflector on its axis and rotation of the shaft turns the casing therewith, a clutch member secured to the lower end of the shaft, an arm adapted to swing about the axis of said shaft, a lever pivotally connected to said arm, a handle on one end of the lever, a clutch member on the opposite end thereof adapted for engagement with the clutch member on the shaft, guide means holding said clutch members in alignment when disengaged, yieldable means urging said clutch members into engagement, the lever being manually slidable on its pivot to disengage the clutch members and allow turning of the lever and arm about the axis of the shaft.

3. In a spotlight, a stationary bracket, a vertical shaft rotatably mounted in the said bracket and movable vertically therein, a casing rotatable with the said shaft, a reflector mounted in the casing to turn on a horizontal axis, means connecting the shaft with the reflector and with the casing whereby vertical movement of the shaft turns the reflector on its axis and rotation of the shaft turns the casing therewith, a stationary clutch member on said bracket, a movable clutch member, yieldable means normally urging the movable clutch members into engagement with the stationary clutch member, the clutch members when engaged locking the shaft from movement, and manually operable means for releasing the clutch members to allow movement of the vertical shaft.

4. In a spotlight, a stationary bracket, a vertical shaft rotatably mounted in the said bracket and movable vertically therein, a casing adapted to rotate with said shaft, a reflector mounted in said casing to turn on a horizontal axis extending at a right angle to the longitudinal axis of the casing, the reflector being mounted to throw the light beam at a slight angle to the axis of said casing, means connecting the shaft with the reflector and with the casing whereby vertical movement of the shaft turns the reflector on its axis and rotation of the shaft turns the casing therewith and manually operable means for locking the said shaft from movement.

5. In a spotlight, a casing mounted to turn on a vertical axis, a reflector mounted in the casing to turn on a horizontal axis, a vertical shaft extending into the casing, means connecting the shaft with the reflector and with the casing whereby vertical movement of the shaft turns the reflector on its axis and rotation of the shaft turns the casing therewith, an arm normally rotatable with the shaft, a bushing pivotally mounted in the end of the

- arm, a handle slidable longitudinally of the bushing and adapted when turned in a vertical plane to move the shaft longitudinally, a clutch member carried by the handle, a companion clutch member secured to the lower end of the shaft, a spring normally urging the said clutch members into engagement, a stationary clutch member and a movable clutch member, a spring normally urging the movable clutch member into engagement with the stationary clutch member, the said last named clutch members when so engaged preventing movement of the shaft, and manually operable means for freeing the clutch members to allow movement of the shaft.
6. In a spotlight, a casing mounted to turn on a vertical axis, a reflector mounted in the casing to turn on a horizontal axis, a vertical shaft extending into the casing, means connecting the shaft with the reflector and with the casing whereby vertical movement of the shaft turns the reflector on its axis and rotation of the shaft turns the casing therewith, an arm normally rotatable with the shaft, a bushing pivotally mounted in the end of the arm, a handle slidable longitudinally in the bushing, a clutch member carried by the handle, a companion clutch member secured to the lower end of the shaft, yieldable means normally urging the clutch members into engagement, a stationary clutch member, a movable clutch member, yielding means urging the movable clutch member into engagement with the stationary clutch member, a lever pivoted to said arm and secured to the movable clutch member, a toggle joint between the arm and lever adapted in one position to disengage the movable clutch member from the stationary clutch member and adapted in the other position to allow engagement of the clutch members by the yieldable means, and manually operable means for moving the toggle joint from one position to the other.
7. In a spotlight, a casing mounted to turn on a vertical axis, a reflector mounted in the casing to turn on a horizontal axis, a shaft extending into the casing, means connecting the shaft with the reflector and with the casing whereby vertical movement of the shaft turns the reflector on its horizontal axis and rotation of the shaft turns the casing therewith, an arm rotatable about the shaft, a bushing carried by the said arm, a handle slidable in the bushing, a clutch member on the lower end of the shaft, a companion clutch member carried by the handle, yieldable means between the bushing and handle normally urging the clutch member of the handle into engagement with the clutch member of the shaft, and manually operable means for locking the shaft from movement.
8. In a spotlight, a casing mounted to turn on a vertical axis, a reflector mounted in the casing to turn on a horizontal axis, a vertical shaft extending into the casing, means con-

necting the shaft with the reflector and with the casing whereby vertical movement of the shaft turns the reflector on its horizontal axis and rotation of the shaft turns the casing therewith, a handle extending at a right angle to the axis of the shaft and normally connected to turn the shaft when moved through a horizontal plane, and manually operable means for locking the shaft from movement.

9. In a spotlight, a casing, a shaft extending into the casing and turnable therewith, a reflector pivotally mounted in the casing, means connecting the shaft with the reflector and with the casing whereby longitudinal movement of the shaft turns the reflector on its axis and rotation of the shaft turns the casing therewith, a handle for turning the shaft, clutch means between the handle and shaft, yieldable means normally holding the clutch means in engagement, and a pivotal support for the handle whereby movement of the handle on its pivot produces longitudinal movement of the shaft.

10. In a spotlight, a casing mounted to turn on a vertical axis, a reflector mounted in the casing to turn on a horizontal axis, a vertical shaft extending into the casing, means connecting the shaft with the reflector and with the casing whereby vertical movement of the shaft turns the reflector on its horizontal axis and rotation of the shaft turns the casing therewith, and a pivotally mounted handle adapted when moved through a horizontal plane to turn the shaft on its axis and adapted when moved in a vertical plane to move the shaft longitudinally.

11. In a spotlight, a casing mounted to turn on a vertical axis, a reflector pivotally mounted in the casing to turn on a horizontal axis, a shaft mounted to turn with the casing, the shaft being movable longitudinally in relation to the casing to turn the reflector on its pivot, a handle for turning the shaft on its axis, means connecting the shaft with the casing so that by turning the shaft the casing is turned therewith, and means for locking the shaft in stationary position.

12. In a spotlight, a casing mounted to turn on a vertical axis, a reflector mounted in the casing to turn on a horizontal axis, a vertical shaft extending into the casing, means connecting the shaft with the reflector and with the casing whereby vertical movement of the shaft turns the reflector on its horizontal axis and rotation of the shaft turns the casing therewith, a stationary clutch member positioned about the shaft and through which the shaft is normally movable, the said clutch member being slotted, a second clutch member movable into engagement with the slotted clutch member to compress the slotted ends thereof onto the shaft and lock the shaft from movement.

and manually operable means for engaging and disengaging the clutch members.

13. In a spotlight, a casing mounted to turn on a vertical axis, a reflector pivotally mounted in the casing to turn on a horizontal axis, a vertical shaft extending into the casing and connected to turn the reflector on its pivot by vertical movement of the shaft, a partition in the casing provided with a vertical slot, and a lug on the shaft riding in the slot whereby the casing may be turned by rotation of the shaft.

In testimony whereof I sign this specification.
